US0D1078440S

(12) **United States Design Patent** (10) **Patent No.:** **US D1,078,440 S**
(45) **Date of Patent:** **** Jun. 10, 2025**

(54) **FASTENING HOOK**

(71) Applicant: **Shenzhen Reborn AeroTech Technology Co., Ltd.**, Shenzhen (CN)

(72) Inventors: **Zhaoshuang Wu**, Shenzhen (CN); **Chong Guo**, Shenzhen (CN); **Jianhua Xie**, Shenzhen (CN); **Qing Li**, Shenzhen (CN); **Haotian Chen**, Shenzhen (CN)

(73) Assignee: **Shenzhen Reborn AeroTech Technology Co., Ltd.**, Shenzhen (CN)

(**) Term: **15 Years**

(21) Appl. No.: **29/966,403**

(22) Filed: **Oct. 1, 2024**

(30) **Foreign Application Priority Data**

Aug. 13, 2024 (CN) 202430511944.X

(51) **LOC (15) Cl.** **08-07**

(52) **U.S. Cl.**

USPC **D8/331**

(58) **Field of Classification Search**

(57) **CLAIM**

The ornamental design for a fastening hook, as shown and described.

DESCRIPTION

FIG. 1 is a front perspective view of a fastening hook, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the fastening hook, which form no part of the claimed design.

1 Claim, 8 Drawing Sheets
